UNITED STATES PATENT OFFICE.

CLARENCE D. PETERS, OF VICTORIA, ILLINOIS.

PIPE-WRENCH.

No. 906,277.

Specification of Letters Patent.

Patented Dec. 8, 1908.

Application filed August 19, 1908. Serial No. 449,278.

To all whom it may concern:

Be it known that I, CLARENCE D. PETERS, a citizen of the United States, residing at Victoria, in the county of Knox and State of Illinois, have invented new and useful Improvements in Pipe-Wrenches, of which the following is a specification.

This invention relates to pipe and rod wrenches, the object of the invention being 10 to provide a wrench which will accurately adjust itself to the different sizes of pipes and rods for which it is adapted, which will not slip and cut the pipe, which will quickly and firmly grip and securely hold different sizes 15 of pipes without liability of crushing the thinnest pipe, and which will effectually prevent displacement of small rods and pipes while the same are being gripped.

The invention consists of the features of 20 construction, combination and arrangement of parts hereinafter fully described and claimed, reference being had to the accompanying drawing, in which:—

Figure 1 is a side elevation of a wrench 25 constructed in accordance with my invention. Fig. 2 is a top plan view or edge view of the same. Fig. 3 is a view similar to Fig. 1 with parts omitted and the jaws shown in closed position. Fig. 4 is a similar view 30 showing still other parts omitted and the jaws in open position.

Referring to the drawing, 1 designates the handle bar or shank of the wrench, which is provided at its forward end with a fixed or 35 stationary jaw 2 of hook form or curved on an arc of a suitable radius. Projecting from the inner end of this jaw at its point of junction with the shank and beyond one of the edges of the latter is a segmentally curved 40 lug 3, and arranged to coöperate with the stationary jaw is a movable jaw 4, the rear end of which movable jaw is bifurcated or segmentally slotted to form a recessed portion 5 to receive and turn upon the lug 3, the 45 opposite arms 6 and 7 of said recessed or bifurcated portion being adapted for respective engagement with shoulders 8 and 9 at the front and rear of the lug to limit the swinging movements of the movable jaw.

The movable jaw is pivotally mounted 50 between the outer ends of a pair of supporting plates 10 upon a pivot pin or bolt 11, the inner ends of which plates are disposed upon opposite sides of the inner end of the stationary jaw or forward end of the shank and

are pivotally supported therefrom upon the opposite ends of a pin or bolt 12 passing therethrough. The movable jaw is thus indirectly pivoted to the stationary jaw or handle so as to adapt it to have a free swinging movement and to assume different positions of adjustment in use. A plate or ribbon spring 13 extends along the edge of the handle from which the lug projects and is rigidly secured at its rear end to said handle 60 and outwardly bent or offset at its forward or free end, which terminates adjacent the rear edge of the lug, to bear against the rear arm 7 of the bifurcated portion of the movable jaw, said spring serving to normally 70 hold the movable jaw closed and permit it to yieldingly open to adjust itself to different sizes of rods or pipes.

A gripping chain 14 is arranged in the form of a loop in the space between the jaws and the inner faces of its links are toothed, as at 15, to bind securely against the engaged rod or pipe. One end of this chain is pivotally connected with the outer end of the jaw 2, as at 16, while the opposite end thereof passes 80 around the free end of the jaw 4 and between a pair of spaced guide plates 17 riveted or otherwise fixedly secured to the opposite faces of said jaw and extending transversely beyond the inner and outer edges of the 85 same. A pin 18 extends between and connects the outer ends of said plates 17 and has pivotally mounted thereon a toothed latch or dog 19 which is normally forced inwardly or toward the outer edge of the free end of 90 the jaw to engage the toothed surface of the free end of the chain and clamp the same against the jaw, by which the chain may be adjusted to engage rods or pipes of different diameters and its free end secured against 95 movement or displacement in adjusted position. The jaw 4 has its free end terminating when in closed position adjacent the free end of the movable jaw and projected outwardly 100 beyond the same so as to facilitate the application of the rod or pipe between the jaws and the removal of the same therefrom, as well as to close the space between the jaws to as great a degree as possible to adapt the chain to surround the inclosed rod or pipe to 105 a maximum extent, while at the same time permitting of a maximum range of adjusting movement to the movable jaw to adapt it and the chain to adjust themselves readily and easily to variations in the sizes of the 110

rods or pipes to be gripped and held or turned. The inner ends of the guide plates 17 are provided with gripping teeth 21 inclining in a direction away from the fixed 5 jaw, and which substantially cover the open space between the ends of the gripping chain when the jaws are closed to engage the portion of the pipe or rod which is not engaged by the chain and to coöperate with the latter 10 to increase the grip or hold upon the object. These toothed gripping portions 21 also serve to engage and retain in position small rods or pipes and prevent displacement thereof while the chain is being brought into 15 gripping engagement therewith.

Fig. 1 shows the wrench adjusted to receive and engage rods or pipes of different sizes within determined limits, and in operation it will be understood that the movable 20 jaw is opened to a sufficient extent to admit the rod or pipe and then allowed to close about the same so as to bring the toothed gripping surfaces into engagement therewith. When the handle 1 is then moved in a direction 25 away from the pivoted jaw, the latter will be closed to a greater extent and the chain drawn into closer gripping engagement with the rod or pipe. As the engaging surfaces are toothed and readily adjust 30 themselves to engage the surfaces of the rod or pipe, it will be apparent that the rod or pipe will be firmly gripped and slipping of the wrench thereon and cutting the surface of the pipe prevented. The harder the degree of 35 pulling strain upon the handle 1 the closer the gripping engagement will be between the gripping surfaces and the rod or pipe, so that slipping of the wrench will be prevented even in turning a refractory rod or pipe. The dog 40 or catch 19 prevents loosening of the chain, but by simply pressing back said dog the free end of the chain may be freed to permit the looped portion thereof to be increased or decreased in diameter for engagement with different sizes of rods or pipes, and then by freeing 45 the dog the spring 20 will project or throw the same again into gripping engagement to securely hold the chain in its newly adjusted position.

50 From the foregoing description, the construction and mode of use of my improved wrench will be readily understood, and it will be seen that it provides a wrench which will quickly and firmly engage and hold a 55 rod or pipe and maintain a tight gripping engagement therewith, and that by reason of the flexibility of the chain and the practically yielding pressure which it exerts and its capacity to accommodate itself to the surfaces 60 of a pipe thin or fragile pipes may be gripped without liability of fracture of the same. In addition to the advantages mentioned, the wrench is simple of construction and may be manufactured and sold at a comparatively 65 low cost.

Having thus fully described the invention, what is claimed as new is:—

1. A wrench comprising a handle carrying relatively movable jaws, a gripping chain terminally connected with one of the jaws, a 70 guide for the free end of the chain upon the other jaw, and a pivoted spring-actuated clamp associated with said guide for clamping the free end of the chain to said jaw.

2. A wrench comprising a handle carrying relatively movable jaws, a gripping chain arranged between the jaws and secured at one end to one of the jaws, a guide for the free end of the chain upon the other jaw, and a spring-actuated clamp upon said guide for 80 securing the free end of the chain to said jaw.

3. A wrench comprising a handle carrying fixed and pivoted jaws, a spring for normally holding the pivoted jaw closed, a gripping chain pivoted at one end to the fixed jaw and in guided connection at its free end with the pivoted jaw, and a spring-actuated locking device upon the pivoted jaw to adjustably 85 secure the free end of the chain thereto.

4. A wrench comprising a handle having 90 relatively movable jaws, a toothed gripping chain arranged between and connected at one end with one of the jaws, plates upon the free end of the other jaw extending inwardly and outwardly therefrom, the outwardly extending portions of the plates forming a guide for the free end of the chain and the inwardly extending portions being toothed to grip the rod or pipe between the ends of the chain, and a locking device pivotally mounted upon 95 the guide for securing the free end of the chain to said jaw.

5. A wrench comprising a handle carrying fixed and pivoted jaws, a spring for normally holding the pivoted jaw closed, a gripping chain pivoted at one end to the fixed jaw, a 105 guiding device for the free end of the chain upon the pivoted jaw, said guiding device having inwardly extending toothed portions to engage the rod or pipe between the ends of the chain and a pivoted spring-actuated locking device upon the guide to engage and 110 secure the free end of the chain to the pivoted jaw.

6. A wrench comprising a handle carrying fixed and pivoted jaws, a spring for normally holding the pivoted jaw closed, a gripping chain pivoted at one end to the fixed jaw, a 115 guide for the free end of the chain upon the free end of the movable jaw, a pivot pin carried by the guide, a locking dog pivotally mounted upon said pin to engage and interlock with the chain, and a spring arranged to normally throw the dog into locking position.

In testimony whereof I affix my signature 125 in presence of two witnesses.
